UNITED STATES PATENT OFFICE.

THOMAS D. COLLINS, OF LOS ANGELES, CALIFORNIA.

GAME.

Application filed April 24, 1923. Serial No. 634,309.

To all whom it may concern:

Be it known that I, THOMAS D. COLLINS, a citizen of the United States, residing at Los Angeles, in the county of Los Angeles 5 and State of California, have invented a new and useful Game, of which the following is a specification:

This invention relates to a game and more especially to a novel form of game 10 board, one of its objects being to provide a board utilizing a pair of closely associated pins fixedly mounted, it being designed to employ a ring to be thrown at the pins for the purpose of "ringing" them, the points 15 counted in determining the result of the game, being determined by the position of the thrown ring relative to the pins.

With the foregoing and other objects in view which will appear as the description 20 proceeds, the invention consists of certain novel details of construction and combinations of parts which will be hereinafter more fully described and pointed out in the claims, it being understood that changes 25 may be made in the construction and arrangement of the parts without departing from the spirit of the invention as claimed.

In the accompanying drawings the preferred form of the invention has been 30 shown.

In said drawings.

Figure 1 is a plan view of the game board, one position of a ring thereon being indicated by full lines.

Figure 2 is a section on line 2—2 Figure 35 1, a cover being shown on the board.

Referring to the figures by characters of reference 1 designated a circular box which can be provided with a lid 2 and secured in

the bottom of the box is a board 3 which 40 may be provided with a soft covering 4 of felt or the like. Secured to the board 3 near the center thereof are upstanding parallel pins 5. Two of these pins are used and they are spaced apart a distance slightly greater than the thickness of the ring 6 constituting the game piece.

In playing the game the ring is tossed at the pins. If both pins are rung a certain number of points are placed to the credit 45 of the player. If the ring encloses or surrounds one pin only another number of points is placed to the credit of the player. Should the rings stand up against both pins the play would have a predetermined value 50 and another value would result should the ring lean against one pin only.

What is claimed is:

1. A game including a box-like structure, a pair of parallel pins upstanding therefrom adjacent its center and a ring constituting a game piece, said pins being spaced apart a distance slightly greater than the thickness of the ring.

2. A game including a box-like structure, a board therein, a pair of pins upstanding from the board adjacent its center, a game piece for ringing one or both of the pins, said pins being spaced apart a distance slightly greater than the thickness of the 70 game piece.

In testimony that I claim the foregoing as my own, I have hereto affixed my signature in the presence of two witnesses.

THOMAS D. COLLINS.

Witnesses:
